Dec. 959

Samuel B. Jerome, of Waterbury Conn.
Letters Patent No 959 - Dated Oct. 20th 1857.

~~~~~  
The schedule referred to in these Letters Patent is making part of the same.  
~~~~~

To all whom it may concern:

Be it known, that I, Samuel B. Jerome, of Waterbury, in the County of New Haven, and State of Connecticut, have invented an original design for clock cases, the construction and operation of which I have described in the following specification and illustrated in the accompanying drawings, with sufficient clearness to enable competent and skillful workmen, in the arts to which it pertains, or is most nearly allied, to make and use my invention.

My said design consists in the combination and arrangement of various architectural mouldings so adapted and placed as to produce a new design for clock cases as hereinafter more fully set forth. In the accompanying drawing.

Fig. 1. is a front elevation, and

Fig. 2. is a side elevation.

The front of the clock case consists of two stiles and a top and bottom rail, the rails being so much thicker than the stiles, as to allow of a small projection, as shown upon the drawings.

The front elevation may be divided into three portions, the base, the dado or die, and the cornice.

The base consists of a plain rectangular plinth A, a weathering B, a quirk C, an astragal D, and a fascia E.

The cornice consists of an astragal F, a fillet I, a scotia canetto or hollow H, a bead G, and a fascia F.

The base and cornice are returned round the ends as shown.

The dado or die occupies the space between the cornice

and base, and is prepared for receiving the door K, which consists of two panels, the upper one of which is glazed: the lower one may be also glazed, or filled with any other substance suitable to the purpose, ornamental or otherwise, as deemed most advisable. The door is recessed back about a quarter of an inch, and is hung to one of the stiles of the dado with butt hinges in the usual manner, as shown on the drawing. The sides between the base and cornice are plain.

The particular improvements which constitute my ^{said} design, and which I claim as having been originally and first invented by me are, the combination and arrangement of various architectural mouldings so as to produce by their relative position, and their combined artistic effect, the design for clock cases hereinbefore set forth.
